Primary Examiner — Dominic V Simone

(74) Attorney, Agent, or Firm — Fross Zelnick Lehrman & Sissu, P.C.; Lawrence E. Apolzon, Esq.

(57) CLAIM

The ornamental design for footwear, as shown and described.

DESCRIPTION

FIG. 1 is a front perspective view of footwear showing my new design;

FIG. 2 is a left side view of the footwear shown in FIG. 1;

FIG. 3 is a right side view of the footwear shown in FIG. 1;

FIG. 4 is a front view of the footwear shown in FIG. 1;

FIG. 5 is a rear view of the footwear shown in FIG. 1; and,

FIG. 6 is a top view of the footwear shown in FIG. 1.

The broken line showing of sole and heel cap in the drawings disclose unclaimed subject matter and form no part of the claimed design.

1 Claim, 6 Drawing Sheets
